UNITED STATES PATENT OFFICE.

MARTIN V. HAMMACK, OF THALIA, VIRGINIA, ASSIGNOR OF ONE-HALF TO
CEPHUS O. GRIMES, OF PORTSMOUTH, VIRGINIA.

DESIGN FOR A BUREAU OR SIMILAR ARTICLE OF FURNITURE.

SPECIFICATION forming part of Design No. 35,947, dated June 10, 1902.

Application filed March 1, 1902. Serial No. 96,341. Term of patent 7 years.

To all whom it may concern:

Be it known that I, MARTIN V. HAMMACK, a citizen of the United States, residing at Thalia, in the county of Princess Anne and State of Virginia, have invented a certain new and useful Design for Bureaus or Similar Articles of Furniture, of which the following is a specification.

My said invention consists in a design for a bureau, dresser, or like article of furniture which is both ornamental and symbolic, as will be hereinafter more fully described.

The accompanying drawing shows a bureau of my design in front elevation.

The main portion of said bureau is suitably arranged with drawers *d* and with a central cabinet provided with a door *d'*. On the front of each drawer is the representation of a star. The door *d'* is also likewise ornamented with a star having a circle in its center within which is a star. The upper frame contains a mirror *m* and is of an ornamental form, as shown. On its top a star is represented at each corner and in the center a crescent or moon within a circular field with a smaller star at one side thereof. The mirror *m* has

star-points indicated thereon by ornamental figures in curved lines surrounded by a border-line similarly formed and composed of short curves or inverted scallops. Altogether the 30 design is highly ornamental, and its leading features being the moon and stars is symbolic of the night.

While the design is intended particularly for bureaus, it will be understood that it may 35 be used for other articles of furniture of a similar nature, such as chiffonniers, wash-stands, cabinets, hall-racks, &c.

Having thus fully described my said invention, what I claim as new, and desire to secure 40 by Letters Patent, is—

The design for a bureau or similar article of furniture, substantially as herein shown and described.

In witness whereof I have hereunto set my 45 hand and seal, at Washington, District of Columbia, this 21st day of February, A. D. 1902.

MARTIN V. HAMMACK. [L. S.]
